UNITED STATES PATENT OFFICE.

CORNELIUS KROLL, OF TULSA, OKLAHOMA.

METHOD OF AND APPARATUS FOR CRACKING PETROLEUM PRODUCTS.

Continuation of application Serial No. 274,850, filed February 4, 1919. This application filed February 9, 1920. Serial No. 357,339.

To all whom it may concern:

Be it known that I, CORNELIUS KROLL, a citizen of the United States of America, a resident of Tulsa, in the county of Tulsa, 5 State of Oklahoma, have invented certain new and useful Improvements in Methods of and Apparatus for Cracking Petroleum Products, of which the following is a full, clear, and exact description, reference being had to the accompanying drawings, forming a part of this specification.

My invention relates to improvements in methods of and apparatus for cracking petroleum products, with special reference 15 to the manufacture of gasoline. It has in view to obtain products of lower boiling points from those heavier portions of petroleum or similar hydrocarbons that can only be obtained by the destructive distillation 20 of such portions.

The commonly employed hydrocarbon, petroleum, is composed of a series of hydrocarbons principally of the paraffin group, the chemical composition of which is designated by the general formula: C_nH_{2n+2} . Each member of the series has a different specific gravity and boiling point, the boiling point becoming higher as the specific 25 gravity increases.

30 In any chemical reaction there exists a certain state or condition of equilibrium, and so, in the cracking reaction of petroleum products or residua, as has been verified by experimentation, there will exist a 35 certain state or condition of equilibrium. For example: if a petroleum residuum is confined in an enclosed vessel which has neither an inlet or an outlet, and this vessel is heated up so that the residuum inside the 40 vessel was subjected to a temperature of 800° F., and a pressure of 80 pounds per sq. in., and maintained under these conditions for an indefinite length of time, and then allowed to cool, we would find upon examination 45 of the residuum so treated that a certain amount of cracking had taken place, only to the point, however, where an equilibrium was reached between the different petroleum molecules, for that particular temperature and pressure. Such equilibrium would not be disturbed by the length of time the residuum would be maintained at the above temperature and pressure, once the equilibrium was reached.

55 In other words, a certain amount of

cracking will take place and further cracking would cease unless the equilibrium were disturbed. This equilibrium is not disturbed by continued maintenance of the residuum under pressure and temperature, 60 but only by removing some of the elements entering into the equilibrium, allowing the reaction to proceed further until equilibrium is again restored. This is a very essential condition which must be obtained in 65 an economic cracking process.

Another desirable condition to be attained is the removal of cracked residua and carbon from the reaction chamber so that its accumulations may not disturb the progress 70 of the process.

Certain processes are carried on in the gaseous phase only, but these have the great disadvantage of not being able to disturb the equilibrium after a certain amount of 75 cracking has been obtained, and the degree of cracking that takes place without the equilibrium being disturbed is not sufficient to make such process commercially economical. My improved process operates in 80 the combination of the gaseous and liquid phases in contact.

In my improved process and apparatus, I have developed a method of carrying the cracking reaction to the end by continually 85 unbalancing the equilibrium of the system in the direction of further and more complete cracking, the resulting product being only a low boiling hydrocarbon, the residuum being a carbon sludge. Thus a complete 90 cracking reaction is obtained, producing only the desired product and the carbon sludge above-mentioned.

Another object of the invention is to very effectively transmit heat through the body 95 of liquid undergoing treatment in a reaction chamber, so as to maintain the liquid at a cracking temperature without undue heat losses. A further object is to eliminate the danger and trouble heretofore incurred by 100 accumulations of carbonaceous residual matter on the surfaces from which heat is transmitted to the oil. Briefly stated, the hydrocarbon liquid may be confined under pressure in a reaction chamber from which the 105 light products are continually permitted to escape in the form of vapor, and the cracking temperature may be maintained by transmitting a heating medium, such as flame and other hot products of combus- 110

tion, through a flue passing through the body of liquid. This flue is surrounded by and in contact with the body of liquid, the heat being transmitted from the outer face 5 of the flue to the surrounding liquid. By continually brushing, or scraping, said outer face of the flue, the heat transmitting face can be kept in a clean condition, free of carbonaceous deposits, and these residual de-

10 posits will drop to inactive points at the bottom of the reaction chamber, where they are out of the sphere of action and from which points they can be easily removed at the will of the operator. It will now be

15 readily understood that the hydrocarbon liquid surrounding the heating medium is very effectively heated by the transmission of heat from the clean outer face of the flue, and the residual matter dropping from this 20 face does not interfere with the transmission of heat to the liquid, nor with the intense cracking reaction which occurs at the flue.

With the foregoing and other objects in view, the invention comprises the novel construction, combination and arrangement of parts hereinafter more specifically described and illustrated in the accompanying drawings, wherein is shown the preferred embodiment of the invention. However, it is 25 to be understood that the invention comprehends changes, variations and modifications which come within the scope of the claims hereunto appended.

Fig. I is a side elevation, partly in section, illustrating a cracking apparatus embodying the features of this invention.

Fig. II is an enlarged longitudinal section taken approximately through the center of the reaction chamber.

40 Fig. III is an enlarged transverse section of the reaction chamber.

Fig. IV is an enlarged fragmentary vertical section illustrating the elements near one end of the reaction chamber.

45 To illustrate one form of the invention, I have shown a long cylindrical reaction chamber A mounted on supports 1 (Fig. I) whereby it is supported in an approximately horizontal position. 2 designates a vapor 50 conductor leading from the top of the reaction chamber, as shown in Fig. I, and 3 designates an oil conductor through which a fresh charge may be delivered to the reaction chamber. A horizontally disposed 55 tube, or flue 4, is located within the reaction chamber and secured at its ends to in-turned flanges formed on annular castings 5, the latter being secured to the ends of the reaction chamber. This flue lies below 60 the level of the hydrocarbon liquid, and its outer face is directly exposed to the surrounding liquid.

6 designates a heating chamber (Figs. I and IV) in free communication with the 65 internal flue 4, and 7 designates an outlet

flue through which products of combustion are discharged from the flue 4, the reaction chamber being interposed between said heating chamber 6 and outlet flue 7. Sleeves 8, telescoping with the end portions of flue 4, 70 serve as means for protecting said end portions from direct contact with the flame and hot gases. A burner 9 (Fig. I), located at the heating chamber 6, is adapted to discharge flame and hot gases through the heating chamber 6 and also through the internal flue 4, said flue 4 being open at both ends to provide for the admission and discharge of products by combustion.

It will now be understood that the internal flue 4 is subjected to the intense heat of the flame and hot gases passing from the burner 9, and that the heat is very effectively transmitted from the outer face of the internal flue to the surrounding body of oil 85 in the reaction chamber. It is not necessary to transmit any heat through the bottom of the reaction chamber, in fact, all of the exposed surfaces of said chamber are preferably covered by an enclosing body of heat insulating material 10, shown in Fig. I.

To illustrate a means for removing carbonaceous residual matter from the outer face of the internal flue 4, I have shown a rotatable frame consisting of gear rings 11 95 arranged in the end portions of the reaction chamber and rotatably mounted on rolls 12, the latter being supported by threaded pins screwed into the castings 5; long bars 13 connecting the gear rings 11, and diagonal bars 14 serving as braces for the connecting bars 13. The brushes, or scrapers, 15 may be in the form of sheet metal wings secured at their outer margins to the connecting bars 13 and provided with scraping edges 105 which engage the outer face of the internal flue 4, as shown most clearly in Fig. III. Springs 16 (Fig. III) may be interposed between the scrapers 15 and bars 13 so as to yieldingly force the scrapers into engagement with the flue 4. The gear rings 11 are concentric with the center line of flue 4, and since the connecting bars 13 and scrapers 15 are supported by these gear rings, it will be apparent that a rotary motion of the 110 gear rings will cause the scrapers to travel in circular paths around the outer face of the flue 4. There are four sets of scrapers 15, each set being secured to one of the connecting bars 13, and the scrapers of the 115 several sets are arranged in alternating relation so as to act upon the entire outer face of the tube 4.

The means for rotating the scraping device or brushing device comprises pinions 125 17 arranged within the reaction chamber and meshing with the gear rings 11, said pinions being fixed to a drive shaft 18, one end of which is rotatably mounted in a bearing 19 while the opposite end extends 130

through a stuffing box 20 secured to the reaction chamber. In Fig. I, I have shown a gear wheel 21 secured to the shaft 18 for the purpose of transmitting a rotary motion thereto. Within the reaction chamber, a bearing 22 (Fig. II) is suspended from stay rods 23 having their ends secured to the ends of the reaction chamber.

To provide for the discharge of residuum from the reaction chamber (Fig. I) I have shown a closed residuum chamber 24 having an outlet 25 adapted to be closed by a valve 26, and a residuum conductor 27 leading from the bottom of the reaction chamber to the residuum chamber 24, said conductor 27 having branches leading to different portions of the bottom of the reaction chamber and each of said branches being provided with a valve 28. 29 designates a valve located in the conductor 27.

When the apparatus is in service, the contents of the reaction chamber are maintained under a high pressure, for example, about 80 pounds per square inch, and the carbonaceous residuum can be easily removed without materially lowering this pressure. When the outlet valve 26 (Fig. I) is closed to prevent the escape of fluid under pressure from the residuum chamber 24, the valves 28 and 29 may be opened to allow the residuum in the bottom of the reaction chamber to be discharged by the fluid pressure within said chamber. If this is done the residuum will flow through the conductor 27 and into the chamber 24 until the pressure in chamber 24 is equal to the pressure in the reaction chamber, whereupon the valves 28 and 29 may be closed and the valve 26 may be opened to discharge the residuum from chamber 24.

The reaction chamber is operated under pressure, depending upon the product to be treated, the average pressure being approximately 80 pounds per square inch, and the temperature of the contents of the reaction chamber is maintained at such a degree (approximately 700° F. to 800° F.) as to cause distillation at the pressure maintained, distillation under such conditions being a destructive distillation resulting in cracking of the heavy hydrocarbon which is forced into the reaction chamber through the inlet pipe 3, shown in Fig. I. The light hydrocarbons resulting from the cracking reaction are continually discharged through the vapor pipe 2, and the residuum may be drawn off at intervals through the valves 28 and 29, as previously pointed out. The operation is thus rendered continuous and the entire system is a comparatively simple apparatus within the control of the operator at all times. I do not deem it necessary to show the dephlegmator, condenser or pressure regulating valve usually found in an apparatus of this kind, for all of these ele-

ments are old and well understood in this art.

The flue 4 is separated from the bottom of the reaction chamber to provide for the accumulation of carbonaceous matter at 70 points entirely below the flue, and the scraping devices engaging the outer faces of the flue may be rotated continually to remove the carbonaceous matter which drops to the bottom of the reaction chamber where it will 75 not in any way interfere with the transmission of heat to the oil. Furthermore, this residual matter is not disturbed or agitated by the thermo-circulation resulting from the transmission of heat from the internal flue 80 to the oil. The oil contacting with the outer face of the flue 4 is constantly rising and being replaced by comparatively cool oil, so the entire body of oil is very effectively maintained at a high temperature by 85 the heat transmitted from the outer face of the flue 4.

As a specific illustration of suitable dimensions and proportions of elements forming part of the new apparatus, I will state 90 without in any way limiting the scope of the claims that the reaction chamber may be 6½ feet in diameter and twenty feet long; the internal flue 4 may be 20 inches in diameter. In the treatment of gas or fuel oil to obtain 95 a product having an end point lower than 460° F., the contents of the reaction chamber may be maintained at a temperature say up to 800° F. and under a pressure up to about 80 pounds per square inch. The level of the 100 liquid should be maintained entirely above the flue 4, as suggested by Fig. III. The reaction chamber may be provided with a man-hole normally closed by a cover 30, shown in Fig. III.

This application is a continuation of my prior application Serial No. 274,850, filed February 4, 1919.

I claim:

1. The method of manufacturing petroleum products consisting in subjecting a body of suitable liquid hydrocarbon to be treated within an enclosed reaction chamber under pressure to an internal source of heat surrounded by the liquid hydrocarbon so as 110 to effect cracking and the distillation and separation of the lighter products produced, removing the lighter products as they are produced, and forcibly removing accumulations of heavier residua from between the 115 internal source of heat and the surrounding body of hydrocarbon to maintain the heat action at a desired maximum and a resulting unbalancing of equilibrium by the continual removal of the cracked products and the 120 residua from the sphere of action.

2. In the art of cracking hydrocarbons, the method which comprises confining a body of the hydrocarbon liquid to be cracked in a reaction chamber, transmitting heating 130

medium through a flue surrounded by said liquid, so as to maintain the liquid at a cracking temperature, and maintaining the contents of the reaction chamber under pressure, at the same time removing carbonaceous matter from the outer face of said flue to a relatively inactive portion of said reaction chamber.

3. In the art of cracking petroleum hydrocarbons, the method which comprises confining a body of hydrocarbon liquid in a reaction chamber, transmitting heating medium through a flue entirely below the level of said liquid so as to subject the liquid to the internal heat transmitted from the outer face of the flue, thereby maintaining the liquid at a cracking temperature, conducting vapor from the reaction chamber, maintaining the contents of said reaction chamber under pressure, continually removing carbonaceous matter from the outer face of said flue, and dropping said carbonaceous matter from said flue to a relatively inactive portion of the reaction chamber below said flue.

4. In the art of cracking petroleum hydrocarbons, the method which comprises maintaining a body of hydrocarbon liquid in a large and approximately horizontal cylindrical reaction chamber, transmitting hot products of combustion in an approximately horizontal course through said body of liquid, and from one end thereof to the other, by conducting said products of combustion through an approximately horizontal flue surrounded by the body of liquid, thereby subjecting the surrounding liquid to the heat transmitted from the outer face of said flue so as to maintain the liquid at a cracking temperature, conducting the resultant vapors from said reaction chamber, maintaining the contents of said reaction chamber under pressure, and at the same time forcibly removing carbonaceous matter from said outer face of the flue and dropping said carbonaceous matter from said flue to a relatively inactive portion of the reaction chamber below the flue.

5. In the art of cracking petroleum hydrocarbons, the method which comprises maintaining a body of hydrocarbon liquid in a large horizontal cylindrical insulated reaction chamber, transmitting hot products of combustion through a horizontally disposed flue surrounded by said liquid so as to subject the surrounding liquid to the heat transmitted from the outer face of said flue, thereby maintaining said liquid at a cracking temperature, conducting vapor from said reaction chamber, maintaining the contents of said chamber under a pressure greater than atmospheric pressure, at the same time scraping carbonaceous matter from said outer face of the horizontally disposed flue, permitting such carbonaceous

matter to drop to the bottom of said horizontal reaction chamber, maintaining said bottom at a temperature lower than that of the flue, and discharging carbonaceous matter from the bottom of the reaction chamber 70 while the liquid is subjected to the cracking temperature.

6. In an apparatus for cracking petroleum hydrocarbons, a reaction chamber wherein a body of hydrocarbon liquid is confined under pressure, a conductor whereby a heating medium is transmitted through the body of liquid so as to maintain the liquid at a cracking temperature, and means for removing carbonaceous matter from the outer face 75 of said conductor, the interior of said reaction chamber being provided with an inactive surface adapted to receive the carbonaceous matter passing from the outer face of said conductor.

7. In an apparatus for cracking petroleum hydrocarbons, a reaction chamber wherein a body of hydrocarbon liquid is maintained under pressure, a flue passing through said reaction chamber below the level of the liquid therein, the outer face of said flue being directly exposed to the surrounding liquid, means for heating said flue so as to subject the liquid to heat transmitted from said outer face, and means whereby carbonaceous 90 matter is continually removed from said outer face, the interior of said reaction chamber being provided with an inactive surface adapted to receive the carbonaceous matter passing from said flue.

8. In an apparatus for cracking petroleum hydrocarbons, a reaction chamber wherein a body of hydrocarbon liquid is maintained under pressure, a flue passing through said reaction chamber below the level of the liquid therein, the outer face of said flue being directly exposed to the surrounding liquid, means for heating said flue so as to subject the liquid to heat transmitted from said outer face, the bottom of said reaction 105 chamber having an inactive surface, said flue being separated from the bottom of said reaction chamber to provide for the accumulation of carbonaceous matter at points entirely below said flue, and a scraping device 110 engaging said outer face of the flue to continually remove carbonaceous matter therefrom.

9. In an apparatus for cracking petroleum hydrocarbons, a reaction chamber wherein a body of hydrocarbon liquid is maintained under pressure, a flue passing through said reaction chamber below the level of the liquid therein, the outer face of said flue being directly exposed to the surrounding liquid, means for heating said flue so as to subject the liquid to heat transmitted from said outer face, said flue being separated from the bottom of said reaction chamber to provide for the accumulation of carbonaceous 120 125 130

matter at points entirely below said flue, and a scraping device engaging said outer face of the flue to continually remove carbonaceous matter therefrom, said scraping device comprising a scraper-carrying frame surrounding said flue, and means for rotating said frame to revolve its scraping elements around the axis of said flue.

10. In an apparatus for cracking petroleum hydrocarbons, a reaction chamber wherein a body of hydrocarbon liquid is maintained under pressure, a flue passing through said reaction chamber below the level of the liquid therein, the outer face of 15 said flue being directly exposed to the surrounding liquid, means for heating said flue so as to subject the liquid to heat transmitted from said outer face, said flue being separated from the bottom of said reaction 20 chamber to provide for the accumulation of carbonaceous matter at points entirely below said flue, and a scraping device engaging said outer face of the flue to continually remove carbonaceous matter therefrom, said 25 scraping device comprising ring-gears surrounding end portions of said flue, scraper supporting members connecting said gears, and driving pinions meshing with said gears.

30. 11. In an apparatus for cracking petroleum hydrocarbons, a reaction chamber wherein a body of hydrocarbon liquid is maintained under pressure, an approximately horizontal flue extending through 35 said reaction chamber below the level of the liquid therein, the outer face of said flue being directly exposed to the surrounding liquid, a source of heat from which hot products of combustion are transmitted 40 through said flue so as to subject the surrounding liquid to heat transmitted from the outer face of the flue, said approximately horizontal flue being separated from the bottom of said reaction chamber to provide for 45 the accumulation of carbonaceous matter at points entirely below said flue, and a scraping device rotatable around said flue and engaging the outer face thereof to continually remove carbonaceous matter therefrom.

50. 12. In an apparatus for cracking petroleum hydrocarbons, a large cylindrical horizontally disposed reaction chamber wherein a body of hydrocarbon liquid is maintained under pressure, heat insulating material enclosing said reaction chamber, an open flue extending from one end of said reaction chamber to the other, said flue being in an approximately horizontal position below the level of the liquid and above the bot-

tom of the reaction chamber to provide for 60 the accumulation of carbonaceous matter entirely below said flue, the outer face of said flue being directly exposed to the surrounding liquid, a source of heat from which hot products of combustion are transmitted 65 through said flue so as to maintain the liquid at a cracking temperature, a vapor conductor through which the cracked products are removed from the reaction chamber, a scraping device engaging the said outer face of 70 the flue, and means for rotating said scraping device around said flue to continually remove carbonaceous matter therefrom.

13. In an apparatus for cracking petroleum hydrocarbons, a reaction chamber 75 wherein a body of hydrocarbon liquid is maintained under pressure, a flue passing through said reaction chamber below the level of the liquid therein, the outer face of said flue being directly exposed to the surrounding liquid, means for heating said flue so as to subject the liquid to heat transmitted from said outer face, the bottom of said reaction chamber having an inactive surface, means whereby carbonaceous matter 80 is continually removed from said outer face and dropped onto said inactive surface, a residuum conductor leading from the bottom of said reaction chamber to provide for the discharge of said carbonaceous matter, and 85 a valve controlling the discharge through said conductor.

14. In an apparatus for cracking petroleum hydrocarbons, a reaction chamber wherein a body of hydrocarbon liquid is 90 maintained under pressure, a flue passing through said reaction chamber below the level of the liquid therein, the outer face of said flue being directly exposed to the surrounding liquid, means for heating said flue 100 so as to subject the liquid to heat transmitted from said outer face, the bottom of said reaction chamber being separated from said flue so as to be entirely beyond the means for heating the liquid, means whereby 105 carbonaceous matter is continually removed from said outer face and permitted to drop to the bottom of said reaction chamber, a residuum chamber connected to different portions of the bottom of said reaction 110 chamber, a valve controlling the escape of fluid under pressure from said residuum chamber, and a valve adapted to control communication between said reaction chamber and residuum chamber.

In testimony that I claim the foregoing I hereunto affix my signature.

CORNELIUS KROLL.
